(57) CLAIM

The ornamental design for a head wrap, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of a head wrap;

FIG. 2 is a front view thereof;

FIG. 3 is a rear view thereof; and,

FIG. 4 is a rear view of the head wrap shown in a position of use.

The broken line outline of the partial human figure in FIG. 4 assists in illustrating how the claimed design may appear when worn, but forms no part of the claimed design. The broken line outline of the head wrap and unshaded surface areas within the broken line areas define portions of the head wrap that form no part of the claimed design.
